Primary Examiner—Terry A. Wallace*(74) Attorney, Agent, or Firm*—Michael T. YorkCLAIM

The ornamental design for a golf cart cooler, as shown and described.

DESCRIPTION

FIG. 1 is a perspective view of the golf cart cooler, the broken lines showing the golf cart are for illustrative purposes only and form no part of the claimed design;
 FIG. 2 is a side view thereof, and the opposite side is a mirror image thereof;
 FIG. 3 is a rear view thereof;
 FIG. 4 is a front view thereof;
 FIG. 5 is a top view thereof; and,
 FIG. 6 is a bottom view thereof.
